METHOD OF APPLYING CLOSURES
TO CONTAINERSEmerson E. Hogg, New Kensington, Pa., assignor
to Aluminum Company of America, Pittsburgh,
Pa., a corporation of Pennsylvania

Application August 2, 1940, Serial No. 349,745

4 Claims. (CL. 226—80)

This invention relates to a method of uniting closures with containers.

In the closure industry, a type of metal cap, often identified as a snap-on or pry-off cap, has been known for years. These caps are retained by inwardly disposed projections that cooperate with a suitable bead on the container, the number and size of such projections being such that the cap skirt can be flexed to a shape permitting passage of the projections past the container bead. The commercial success of preformed snap-on or pry-off caps has been retarded by variations in the sealing characteristics of the caps. Many do not provide an hermetic seal, and many, on the other hand, are so tightly applied that they can only be removed by strenuous efforts. These disadvantages result mainly from variations in the dimensions of both caps and container finishes that are unavoidable in large volume production of caps and containers.

To eliminate these disadvantages attending the use of preformed snap-on or pry-off caps, it has been suggested that the retaining projections or lugs be formed in the cap skirt above the usual bottom bead or wire edge when the cap is in sealing position on the container. However, this suggestion, to the best of my knowledge, has been made only in connection with caps of relatively deep skirts and containers with small necks and relatively high compressive strengths.

Accordingly, it is an object of this invention to provide a package with a cap of the pry-off type which is assured of hermetic sealing properties regardless of whether the package is of the vacuum type or must maintain internal pressures greater than atmospheric. It is a further object to provide an easily opened and re-usable package in which the retaining lugs of the cap are located in the wire edge, and are tailor-made in the sense of being formed when the cap is in sealing position on the container. It is an additional object to provide a package that is characterized by a shallow, flexible metal cap having lugs formed in situ for affixation to a wide-mouth container, including such relatively fragile vessels as thin glass tumblers. Still another object is the provision of a novel method of sealing to accomplish the foregoing objects in which the cap is maintained after affixation in a stressed condition resistant to deformation.

The manner in which these objects are obtained, together with their attendant advantages, will be better understood from the following detailed description of the invention with reference to the drawing, in which:

Fig. 1 is a view of the cap in elevation before affixation to a container;

Fig. 2 is an enlarged view in elevation of the cap secured to a suitable container;

Fig. 3 is an enlarged sectional view taken on the line III—III of Fig. 2;

Fig. 4 is an enlarged sectional view of a fragment of the cap and container before sealing;

Fig. 5 is an enlarged sectional-elevational view of the cap and container showing the manner of maintaining the cap in sealing position for affixation; and

Fig. 6 is an enlarged view illustrative of the method provided by this invention for forming the securing lugs.

With reference now to Figs. 1, 2, and 3 in particular, the cap 10 comprises a one-piece, shallow sheet metal shell of the gauges customarily used for caps, having a depressed top center panel 11, an initially flat peripheral top portion 12, and a continuous skirt 13 terminating in an outwardly turned wire edge 14. Carried within the annular channel formed by the depressed center panel 11 and peripheral portion 12 is a resilient sealing gasket 15, which is preferably made of a relatively plastic rubber formulation in a flat ring-like shape. The skirt may be knurled, if desired, to provide corrugations.

30 To affix the cap 10 to a suitable container 17, a number of indentations or lugs 18 are formed from the wire edge 14 in a manner hereinafter described. The number, shape, and size of the lugs are immaterial so long as they permit the cap skirt to flex under pry-off pressure to a polygonal shape that allows passage of the container mouth without permanent deformation of the lugs. However, the lugs are also preferably of such number that they are uniformly spaced circumferentially and of such a size that the larger dimension extends circumferentially of the wire edge. But it is recognized that the lugs for some purposes may be created in series of two or more relatively small slightly spaced lugs, the several series then being uniformly spaced circumferentially of the wire edge.

The container 17, shown in the several figures, is a glass tumbler having a thin wall 19 and a wide mouth defined by an annular, continuous mouth bead 20. The bead 20 may be substantially a semi-circle extending outwardly of the top of the mouth rim. However, I wish it to be understood that, regardless of the cross-sectional shape of the mouth bead, only the shape of certain portions of that part of the bead lying outwardly of

the uppermost part of the mouth rim is of consequence to my invention. With respect to this segment of the bead 20, it is necessary that the upper portion 21 be divergent from the crest of the bead to permit the peripheral cap portion 12 and gasket 15 to be deflected or wrapped about it as shown in Figs. 2, 3, 5, and 6. It is likewise essential that the aforesaid outer segment of the glass bead 20 be provided with a surface 22 that converges downwardly from a diameter equal to the maximum outside container diameter through the bead, and of suitable angularity radius to permit proper grip or hook of the lugs 18 thereon. Preferably, however, the surface 22 is provided with a convex, cross-sectional contour. Thus, although this invention is particularly adaptable to the sealing of containers having relatively small arcuate mouth beads such as the so-called "safety edge" and "chipless" beads, the mouth bead may be of varying cross-sectional shapes so long as the above-mentioned conditions are maintained.

It will be appreciated by those skilled in the art that the inevitable variations in dimensions of both caps and containers make it a difficult problem to provide sufficient hook of the lugs 18 on the bead portion 22 to assure an hermetic seal and also acceptable characteristics of removability that permit preservation of the general shape of the cap and lugs for reclosure purposes. This problem of satisfactory affixation is made even more troublesome by the fact that neither the pressure applied to the top of the cap to create the seal by compression of the sealing gasket, nor the pressure applied to form the lugs, can, as a practical matter, be adjusted to accommodate the dimensional variations of each cap and container to assure the position of the wire edge 14 and the degree of indentation of that wire edge, that make possible the formation of lugs that grip the container bead in the optimum manner.

I have found that the creation of a stressed condition in the cap shell during the formation of the lugs and the subsequent maintenance thereof will provide the necessary factor of dimensional accommodation. This stressed condition is induced by applying sealing pressure to the top of a cap of suitable skirt length in such a manner that not only is the sealing gasket compressed and wrapped about the top bead portion 21, but the peripheral cap portion 12 is also similarly wrapped or deflected prior to formation of the lugs 18. This wrapping or deflection of the cap, together with the compression of the gasket, produces at each of the subsequently formed lugs a C clamp of a self-maintained nature on radial planes extending through the lugs. The maintenance of this stressed condition of the cap subsequent to affixation is materially assisted by the depressed center panel 11, which resists the tendency of the cap to bow or arch across the entire diameter when the peripheral portion 12 is deflected.

The manner of initially producing the combination of cap and container shown in Fig. 2 is illustrated by Figs. 4, 5, and 6. Fig. 4 shows the cap 10 resting loosely on the mouth of the container 17. Thereafter pressure is applied, as shown in Fig. 5, to the peripheral cap portion 12 by means of the pressure block 23. The pressure block has a cap recess or seat 24 that is provided with an upwardly converging surface 25 which contacts only the peripheral cap portion 12 so that lowering of the pressure block flexes down-

wardly the portion 12 and compresses the sealing gasket 15 to lower the wire edge 14 into position for formation of the lugs 18. This position is one that is determined by the amount of hook or grip of the lugs on the bead portion 22 that is required by the type of package being produced, it being obvious that a vacuumized package will require less hook than one maintaining internal pressures greater than atmospheric. In any event, the position should be one in which the entire wire edge, as shown in Fig. 5, is appreciably below the line A—B, which is the horizontal plane of juncture of the bead portion 22 with the portion thereabove.

While the cap is maintained in the aforescribed position and condition, the desired number of lugs 18 equally spaced are formed by pressure applied inwardly against the wire edge 14 by a like number of pressure elements, such as those fragmentarily shown in Fig. 6 and identified by the reference numeral 26. The pressure elements 26 are preferably yieldably applied and simultaneously actuated. The lugs produced by such local deformation of the wire edge in the direction of and against the container will then grip the surface of the previously juxtaposed convergent bead portion 22, since they are formed primarily by lateral transposition of the wire edge.

It has been my experience with this manner of cap affixation that the top peripheral portion 12 between lugs 18 has a tendency, under some circumstances, to arch or bow upwardly subsequent to removal of external top pressure. This, of course, tends to lift the wire edge intermediate the lugs, which portions in addition are likely to expand outwardly. These conditions may be produced by excessive top pressure, and they are naturally aggravated in packages having internal pressures greater than atmospheric after the time of sealing. These tendencies toward deformation may also be a result of the reactive force generated by the local deformation of the wire edge 14 to form the lugs 18. Regardless of the cause or causes, I consider it highly desirable to prevent the occurrence of these conditions or tendencies since they lead to the production of "leakers" or non-hermetic packages.

To prevent occurrence of the aforescribed conditions I have found that portions of the wire edge intermediate the lug areas should have pressure maintained thereagainst during formation of the lugs which will tend to deflect such portions downwardly and that confinement of the cap skirt portion against radial expansion is likewise desirable. The amount of pressure applied to such intermediate portions for this purpose may vary, depending upon whether a pronounced downward bow of the intermediate wire edge portions is desired, or merely a slight deflection sufficient to reinforce the affixed cap against peripheral arching of the top surface in the opposite direction is sought. This manner of creating resistance to top bowing or arching depends, for the most part, on the fact that formation of the lugs, during the existence of the deflecting pressure against the intermediate wire edge portions, tends to give the deflected intermediate portions a permanent set whether or not the elastic limit of the wire edge is exceeded by the deflection, since the lugs prevent circumferential distribution of the deflection throughout the entire wire edge.

A convenient manner of providing this latter phase of my preferred manner of affixation of

the cap is also shown in Figs. 5 and 6 wherein the pressure block 23 is provided with depending legs 27. The legs preferably have arcuate pressure surfaces 28 which, when the pressure block 23 is fully lowered, bear downwardly against equally spaced portions of the wire edge 14 at points intermediate the portions to be deformed into the lugs, as shown in Fig. 5. Suitable openings 29 between the legs 27 permit free access of the pressure elements 26 to the wire edge, as is illustrated in Fig. 6. The desired confinement of the cap skirt is easily secured by making the diameter across the legs 27 such that the recess so formed is only large enough to receive the cap skirt 13 exclusive of the wire edge 14. Thus, the package is assured of an affixed cap that will retain its desired shape when the pressure block is removed.

It is apparent that the cap 10 affixed to the container 17, as illustrated in Fig. 2 by the manner illustrated by Figs. 4, 5, and 6, is removable in the same manner as a preformed snap-on cap of conventional design. In other words, the cap is removable upon application of pressure upwardly against the wire edge 14 in order to flex the cap skirt sufficiently to permit the lugs 18 to ride over the container bead 28. It will also be realized that any cap so fitted to a particular container can be readily re-applied for temporary reclosure of the container in the manner of the ordinary snap-on cap.

I wish it to be understood that, although the provision of a shallow-skirted lug type of pry-off cap in combination with a thin glass tumbler is an important phase of my invention, the invention is in no way so limited; accordingly, with the intent to include all modifications and embodiments of this invention that come within the scope and spirit of the appended claims, I claim:

1. In a method of affixing a cap including a resilient sealing gasket and a cup-like shell terminating in a beaded edge to a container having an annular mouth bead comprising a portion outwardly divergent from the crest of the mouth rim and a portion convergent towards the body portion of the container, the steps comprising deflecting both said shell and said sealing gasket about said divergent bead portion by pressure applied against the top of said shell, applying pressure downwardly against a plurality of portions of said beaded edge, and, while maintaining said pressures, deforming said beaded edge inwardly at a plurality of points intermediate the aforesaid stressed beaded edge portions to form lugs gripping said convergent bead portion.

2. In a method of affixing a cap including a

resilient sealing gasket and a cup-like shell terminating in an outwardly turned beaded edge to a container having an annular mouth bead comprising a portion outwardly divergent from the crest of the mouth rim and a convex portion converging towards the body portion of the container, the steps comprising deflecting both said shell and said sealing gasket about said divergent bead portion by pressure applied to the peripheral top portion of said shell, bowing downwardly a plurality of uniformly spaced portions of said beaded edge, and, while maintaining said deflected and bowed conditions, deforming said beaded edge inwardly at a plurality of points intermediate the aforesaid bowed beaded edge portions to form lugs gripping said convex bead portion.

3. In a method of affixing a cap including a resilient sealing gasket and a cup-like shell terminating in an outwardly turned beaded edge to a container having an annular mouth bead comprising a portion outwardly divergent from the crest of the mouth rim and a convex portion convergent towards the body portion of the container, said steps comprising deflecting both said shell and said sealing gasket about said divergent bead portion, applying pressure downwardly against a plurality of uniformly spaced portions of said beaded edge, confining the skirt of said cap against radial expansion, and, while maintaining said pressures and said confined condition, deforming said beaded edge inwardly at a plurality of points intermediate the aforesaid stressed beaded edge portions to form lugs gripping said convex bead portion.

4. In a method of affixing a cap including a resilient sealing gasket and a shallow cup-like metal shell terminating in an outwardly turned beaded edge to a thin glass tumbler having a continuous mouth bead consisting of a convex portion outwardly divergent from the crest of the mouth rim and adjoining said portion a convex portion convergent towards the body portion of the tumbler, the steps comprising deflecting both said shell and said sealing gasket about said divergent bead portion, applying pressure downwardly against a plurality of uniformly spaced portions of said beaded edge, confining the skirt of said cap against radial expansion, and, while maintaining said pressures and said confined condition, deforming said beaded edge inwardly at a plurality of points intermediate the aforesaid stressed beaded edge portions to form lugs gripping said convergent bead portion.
